UNITED STATES PATENT OFFICE.

ZALOS W. SCOTT, OF SANTA BARBARA, CALIFORNIA.

APPARATUS FOR TIGHTENING FORM WIRES.

Application filed May 16, 1923. Serial No. 639,316.

To all whom it may concern:

Be it known that I, ZALOS W. SCOTT, a citizen of the United States, residing at Santa Barbara, in the county of Santa Barbara and State of California, have invented a new and useful Apparatus for Tightening Form Wires, of which the following is a specification.

This invention relates to an apparatus for tightening the wires employed in preventing spreading apart of the opposite side members of forms employed in the construction of concrete walls.

One of the main objects of the invention is to effect tightening of the form wires without weakening them. Ordinarily a form wire is strung through the sides of the form and connected to make an endless band, and a nail or the like is inserted between the opposite members of the band between the form members and is rotated to effect twisting of the wire band, said twisting resulting in shortening of the band so as to make it taut to hold the form members against spreading further apart.

While the wire band is thus being twisted it gets tighter and tighter. Most of the twisting being effected while the band is relatively tight, causes crystallization of the metal of which the wire is made so that, even when the wire does not break at the time of tightening it, it is quite liable to be broken by the extra strain put upon it when the concrete is poured into place between the form members, the weight of said concrete tending to spread the form members further apart and thus exert a pull upon the form wires.

Another object of the invention is to provide for tightening of the form wires without any material crystallization of the metal of which said wires are constructed.

In order to avoid crystallizing the metal of which the form wires are constructed the form wires are twisted while slack and then drawn taut.

The accompanying drawings illustrate the invention:

Figure 1 is a side elevation of an apparatus constructed in accordance with the provisions of the invention, the same being shown in operating position on one of a pair of form members and a form wire being shown connecting the form members and attached to the apparatus. Broken

lines indicate an abutment inserted between the yoke and rotating head.

Fig. 2 is a plan view of Figure 1, omitting the abutment.

Fig. 3 is an enlarged fragmental inverted plan section on the line indicated by 3-3, Figure 1.

Fig. 4 is an end view of the frame looking toward the right in Fig. 1.

Fig. 5 is a side elevation of a portion of the rotating head.

Fig. 6 is an elevation of Figure 4 from the right thereof.

The form wire to be operated on is indicated at 11 and is shown in position to tie together a pair of form members, indicated at 12, between which the concrete is poured to form a wall in a manner well understood in the art relating to the manufacture of reinforced concrete structures. The form wire 11, after being strung between the form members, will be twisted together near its opposite ends by making one turn, as indicated at 13, to produce a band of the form wire. This operation may be performed by hand and the form wire will be more or less slack, as no effort is made to tighten the same by hand. As many form wires as desired may be thus loosely placed in position ready for the tightening operations.

To effect the tightening of the form wire 11, the opposite ends of the wire will be looped over fingers 14 constituting the opposite ends of a rotating head, indicated in general by the character 15. Portions of the wire preferably engage in grooves 16 that lie between the finger 14 and other fingers 17 that are parallel to the finger 14 and that are shorter than the finger 14, as clearly shown in Figure 6. Preferably a half hitch is formed at each end of the wire, the end portions of the wire lying under other portions thereof and upon beveled end faces 18 of the head so that the greater the strain on the wire 11 the more firmly will the underlying portions of the wire be gripped. The wire may be secured to the head by any other suitable means within the scope of the invention. The head 15 is rotatably mounted, in this instance, on the unthreaded shank 19 of a screw 20 which is threaded through a nut 21 that constitutes the intermediate portion of a frame 22, said frame, in this in-

stance, being U-shaped or in the form of a yoke. The opposite ends of the yoke are bifurcated, as indicated at 221, so as to embrace the upright of one of the form members 12.

Though not absolutely essential it is preferable to clamp the yoke 22 to the form member and, for this reason, one of the bifurcated ends 221 of the yoke is provided with a clamping or set screw 23 adapted to engage the form member 12 that is embraced by the bifurcated ends of the yoke. Preferably the bifurcated ends are offset in opposite directions from the plane of the yoke body so that the yoke legs, when in position on the form member, will not lie centrally with respect to said form member but will be more or less eccentric thereto for a purpose hereinafter mentioned.

20 The head 15 is held in position by a washer 24 on the screw and a pin 25 extending transversely through the screw. The outer end of the screw 20 is provided with a suitable handle 26 whereby to forcibly rotate the screw.

25 The apparatus described above operates as follows:

Assuming that the form wire has been placed in position, as above described, with 30 its ends connected to the head 15, the operator will grasp the head 15 and rotate it in the direction to further twist the wire 11 in the same direction as the initial twist 35 13, all of the twisting occurring between the ends of the wire and the adjacent form member 12. While performing this twisting operation, the operator will feed the screw 20 inwardly so as to effect twisting while maintaining the wire in a slack condition. This is quite important so as to 40 prevent crystallization of the metal of which the wire is made, since crystallization would materially lessen the strength of the wire and make it liable to break under the strain produced when the concrete is poured 45 into the form.

50 After the head 15 has been rotated to twist the opposite portions of the wire together for a sufficient number of turns to insure against parting of the wire band at the joint thus effected, the head 15 will be held against rotation by the operator's hand or, preferably, a suitable abutment, indicated in broken lines at 27 in Figure 1, will 55 be inserted between one leg of the yoke and the head 15 in a manner to prevent rotation of the head when the screw 20 is retracted or screwed outwardly. In this instance, the abutment 27 is merely the handle of a hammer. The screw 20 will then be retracted, thus increasing the distance between the head 15 and the adjacent form member 12, thus pulling the wire 11 taut. In the tight-

ening operation, the twisted portion 13 of the wire is pulled away from the adjacent 65 form member so as to produce a space between the twisted portion and said form member, and this space will then be blocked by inserting a suitable element 28, preferably of triangular cross section with the 70 base of the triangle turned toward the form member and by inserting a suitable wedge 29 between the element 28 and form member.

75 After the foregoing described operations have been performed, the screw 20 will be fed inwardly and the wire disengaged from the head 15, and then the yoke 22 will be unclamped and moved into position for tightening another form wire in the same manner as above described.

80 The offset construction of the bifurcated ends 221 of the yoke legs, hereinbefore referred to, greatly facilitates the inserting of the element 28 and wedge 29 as they can be placed in position by moving them downwardly past the upper leg of the yoke, and said upper leg will not interfere with the use of a hammer to drive the wedge.

I claim:

1. An apparatus of the character described, comprising a frame to engage a form member, a screw threaded through the frame and provided with an unthreaded shank, and a head rotatably mounted on the shank and constructed for securing a form 95 wire thereto.

2. An apparatus of the character described, comprising a frame to engage a form member, a screw threaded through the frame and provided with an unthreaded shank, a head rotatably mounted on the shank with its ends extending on opposite sides of the screw, and means at each end of the head to retain a half hitch of wire. 100

3. An apparatus of the character described, comprising a frame to engage a form member, a screw threaded through the frame and provided with an unthreaded shank, and a head rotatably mounted on the shank with its ends extending on opposite sides of the screw and having a pair of grooves in each end, the ends of the head having beveled faces adjacent to the 110 grooves.

4. An apparatus of the character described, comprising a yoke having its opposite ends bifurcated, said ends being offset in opposite directions from the plane of the yoke body, a screw threaded through the frame and provided with an unthreaded shank, and a head rotatably mounted on the shank and provided with wire engaging means on opposite sides of the screw. 115

Signed at Santa Barbara, Calif., this 8th day of May, 1923.

ZALOS W. SCOTT.
